UNITED STATES PATENT OFFICE.

DAVID MYLES, OF DUNDEE, SCOTLAND.

GOLF-CLUB.

No. 868,687.

Specification of Letters Patent.

Patented Oct. 22, 1907.

Application filed March 6, 1906. Serial No. 304,570.

To all whom it may concern:

Be it known that I, DAVID MYLES, a subject of the King of Great Britain and Ireland, and a resident of Dundee, in the county of Forfar, Scotland, whose post-office address is 111 Cowgate, Dundee, have invented a certain new and useful Improvement in Golf-Clubs, for which I have applied for a patent in Great Britain, No. 5,121, bearing date 11th March, 1905, of which the following is a specification.

10 This invention relates to golf clubs; the object being to improve the driving clubs by adapting them to suit rubber cored or pneumatic balls, although I do not confine their use entirely to these. And in order that my said invention and the manner of performing or carrying the same into effect or practice may be properly understood, I have hereunto appended an explanatory sheet of drawings in which the same reference numerals are used to indicate corresponding parts in all the figures where shown, that is to say;—

15 Figure 1 is a face view showing the head of a driving club, drawn full size. Fig. 2 is a plan of same. Fig. 3 is an elevation showing it in the act of striking a ball and Fig. 4 is a sectional elevation at A. A. (Fig. 1.)

20 In carrying out my invention, I make the head of the driving clubs of metal instead of wood, as at present and of the shape and relative dimensions shown in the drawings. (I have shown on the drawings a full size scale.) as the drawing shows the shaft socket is angled to suit the driving position and the head has a face of approximately even width and its length is twice its width. Relative to any wooden or metal club at present in use the head is shortened very considerably, its depth is the same as the wooden driving clubs, while the weight is the same as the weight of a wooden club used by the same player and for the same purpose. I form the club with a vertically inclined striking face and with an oval projecting portion on its opposite face

forming a balancing weight. I find after making many experiments that the form which gives the best result is the form shown in the drawings the trajectory line 40 being indicated by the line C. C. Fig. 3.

A metal head constructed in the manner and of the dimensions shown is much more efficient, than a wooden club of the same weight, because while it is in perfect balance its bulk is much less thus making it less 45 inclined to swerve when being played in a strong wind. It also provides a harder and more dense material for the ball to bounce from. The advantages over the ordinary wooden driving clubs are as follows;—It will drive a rubber cored ball or a pneumatic ball a greater 50 distance.

My invention has been conceived to meet the altered circumstances which now obtain since the introduction of rubber cored and pneumatic balls, the relative resiliency being now all in the ball, whereas when gutta 55 percha-balls were used the resiliency was partly in the ball and partly in the wooden club. It can be used with greater precision. In cases where the ball is lying "heavy" it will play it "cleaner" being much smaller in the head. The oval projection at the back of the 60 striking center may be more or less thick to suit varying weights.

Having now described my invention, what I claim as new and desire to secure by Letters Patent is;—

A driving club for golf with a shaft socket angled to 65 suit the driving position having a metal head of approximately even width of face, balanced by an enlargement on its rear face, the length of the club being twice its width.

In witness whereof I have hereunto set my hand in presence of two witnesses.

Dated this 23rd day of February, 1906.

DAVID MYLES.
